PORTABLE SHOE RACK FOR FACTORIES

Filed Dec. 4, 1929

FIG. 1.

FIG. 2.

Inventor
William D. Moore
By his Attorney
C. F. P. Moore

UNITED STATES PATENT OFFICE

WILLIAM D. MOORE, OF PORTSMOUTH, OHIO, ASSIGNOR TO THE SELBY SHOE COMPANY,
OF PORTSMOUTH, OHIO, A CORPORATION OF OHIO

PORTABLE SHOE RACK FOR FACTORIES

Application filed December 4, 1929. Serial No. 411,405.

This invention relates to improvements in portable shoe racks used to convey shoes through a factory while in the process of making.

Objects

Among the principal objects which the present invention has in view are: To reduce the number of racks employed in the operation of shoe manufacturing; to reduce the number of operations heretofore employed in the manufacture of shoes incident to the employment of racks for special purposes; and generally to facilitate the operation of manufacturing shoes in factories of large output.

A further object of the invention is to provide an improved portable shoe rack so arranged that the manufacture of shoes will be facilitated and speeded up, thereby saving time and expense.

Other objects will appear as the description proceeds.

Drawings

Figure 1 is a side elevation of my improved shoe rack;

Figure 2 is a sectional view taken on the line 2—2 of Figure 1, the dotted lines showing shoes disposed in positions on the rack;

Figure 3 is a sectional view taken on the line 3—3 of Figure 1, and

Figure 4 is a sectional view taken on the line 4—4 of Figure 3.

Like characters of reference are used throughout the following specification and the accompanying drawings to designate corresponding parts.

Description

In carrying out my invention, I provide a rack having a base 1, side members 2, and mounted upon castors 3. A plurality of trays 4 are arranged in spaced vertical relation between the side members 2. A toe rest rail 5 is arranged longitudinally at a side of each tray 4, and is covered with a felt strip 6.

A peg rail 7 is arranged longitudinally at the side opposite the toe rest rail 5 on each tray 4 and is provided with a plurality of spaced pegs 8 which are adapted to be re-

ceived within the openings in the lasts to retain the shoe and last in position while being worked upon. A plurality of clamp slots 9 are also formed in the peg rail 7, adjacent the pegs 8, and are adapted to receive clamps 55 which engage the bottoms of the heels being glued to the uppers, and the tops of the lasts.

Arranged at the ends of each tray, are the guide rods 10 which slidably support the spring locks 11, which in turn support the ends of the shank rest rails 12, which are covered with felt and have small felt blocks 13 arranged in spaced relation along their upper surfaces. These blocks 13 serve as bumpers for the toes of the shoes to rest between, 65 thereby preventing the shoes from swinging while on the pegs, and from being bruised by contacting with other shoes.

As seen best in Figure 2 of the drawings, the rack herein disclosed is arranged to receive and hold the lasts and shoes under construction in different stages of the manufacture. Thus it will be seen that in the lower rack in the said Figure 2, lasts are disposed more or less freely, and that the rail 12, and 70 the parts connected therewith, have been shifted on the guide rods 10 to remove them from position to obstruct the hold of the said lasts.

The lasts are taken from the lowermost tray 80 in the course of operation and after being provided with the wearing sole on the shoe—or after being what is known in the trade as “lasted”—they are moved on to the position in a factory where the heel of the shoe is applied. Ordinarily, this is done by means of a clamp of usual construction, as shown in Figure 2 of the drawings, which presses the heel of the shoe into position against the shoe structure, including the insole of the shoe. In this position the heel is adhered to the shoe, and the shoe is placed in the rack with the back web of the clamp in the slots 9—and the shank portion of the shoe on the rail 12 85 between the blocks 13.

After the second step, which the foregoing constitutes in the manufacture of shoes, the rack is moved to the next position where the sole and the heel are finished, the clamp 100

which previously held the heel to the shoe having been removed therefrom.

In this position of the shoe shown in the drawings as the third position, the toe of the shoe rests upon the rail 12 between the blocks 13, the rear of the shoe being held in position by the last on the peg 8, thus preventing any side movement of the shoes in the racks or of the toes of the shoes when thus resting.

From this position, the shoes (having been completed) are disposed, as shown in Figure 2 of the drawings by dotted lines, in the final position for delivery to the packer. The shank portion of the shoe rests upon the shank rail 12 and between the felt blocks 13.

It will be seen that during the various movements above indicated, and to accommodate the work performed, the rail 12 may be adjusted back and forth on the rods —10—, the spring locks —11— being pressed to permit the employment of the said rail in the manner indicated.

It will be apparent that the shoes as they are being made, may be placed on the trays in the various desired arrangement, and when the trays are filled, the rack may readily be moved to another place in the factory where other operations will take place.

From the foregoing description, it will be understood that many minor changes in detail of construction may be resorted to without departure from the spirit of the invention.

Having thus described my invention what I claim as new and desire to secure by Letters Patent of the United States is:—

1. A portable shoe rack comprising a frame, a plurality of superimposed trays on said frame, toe rails along corresponding edges of each of said trays, peg rails at the opposite edges of each of said trays, and shank rest rails adjustably mounted on each of said trays interposed between said toe rails and said peg rails.

2. A portable shoe rack comprising a frame, a plurality of superimposed trays on said frame, toe rails along corresponding edges of said trays, peg rails at the opposite edges of said trays, bearing rails at the opposite ends of said trays, and shank rest rails adjustably mounted between the same.

3. A portable shoe rack comprising a frame, a plurality of superimposed trays on said frame, toe rails along corresponding edges of said trays, peg rails at the opposite edges of said trays, shank rest rails adjustably mounted between the same, bearing rails for supporting said shank rail adjustably between said toe and peg rails, and spring locks for holding said shank rest rails in the desired adjusted positions on said bearing rails.

4. A portable shoe rack comprising a frame, a plurality of superimposed trays on said frame, toe rails along corresponding edges of said trays, peg rails at the opposite edges of

said trays, shank rest rails adjustably mounted between the same, bearing rails at the opposite ends of said trays, means for changing the position of said shank rest rails on said bearing rails, and cushioning spacing strips 70 on said peg rails and said shank rest rails.

5. A portable shoe rack comprising a frame, a plurality of superimposed trays on said frame, toe rails along corresponding edges of said trays, peg rails at the opposite edges of said trays, bearing rails at the opposite ends of said trays, shank rest rails adjustably mounted between the same, cushioning strips on said peg rails and said shank rest rails, and spaced cushioning blocks on 80 said shank rest rails.

6. A portable shoe rack comprising a frame, a plurality of superimposed trays fixedly mounted on said frame, said trays having each a toe rail on one side and a peg rail at 85 the opposite side, a shank rail extending lengthwise of each of said trays adjustably mounted for movement crosswise of said trays.
